(57) **CLAIM**

The ornamental design for a modular pneumatic launcher core, as shown and described.

DESCRIPTION

FIG. 1 is a top-front-left perspective view of a modular pneumatic launcher core showing my new design;

FIG. 2 is a bottom-rear-right perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a top-front-left perspective view thereof, wherein the present invention is shown fitted with exemplary equipment; and,

FIG. 10 is a bottom-rear-right perspective view thereof, wherein the present invention is shown fitted with exemplary equipment.

The dashed line showing circular features in FIGS. 1, 2, 3, 4, 7, 8, 9, and 10, and the exemplary equipment shown in FIG. 9, and FIG. 10 are included for the purpose of illustrating environmental structure and forms no part of the claimed design.
